UNITED STATES PATENT OFFICE.

SYDNEY I. PRESCOTT, OF NEW YORK, N. Y., ASSIGNOR TO INTERNATIONAL CIGAR MACHINERY COMPANY, OF NEW YORK, N. Y., A CORPORATION OF NEW JERSEY.

WRAPPING-MACHINE.

1,075,224.

Specification of Letters Patent.

Patented Oct. 7, 1913.

Application filed April 6, 1904. Serial No. 201,861.

To all whom it may concern:

Be it known that I, SYDNEY I. PRESCOTT, a citizen of the United States, residing at New York, county of New York, and State 5 of New York, have invented certain new and useful Improvements in Wrapping-Machines, fully described and represented in the following specification and the accompanying drawings, forming a part of the 10 same.

This invention relates to certain improvements in wrapping machines, and has for one of its objects to produce an improved form of wrapping mechanism which will be 15 simple in construction and efficient in operation.

A further object of the invention is to produce an improved wrapping machine in which the wrapper shall be delivered to the 20 wrapping mechanism by means of a belt and on which the wrapper is held, the belt being rotated to deliver the wrapper and the wrapping mechanism taking the wrapper from the belt.

25 A further object of the invention is to produce an improved wrapping machine in which the wrapper is presented to the wrapping mechanism by a belt upon which the wrapper is held, either the belt or the wrapping mechanism, or both, during the wrapping operation, being given suitable movements to properly present the wrapper to the wrapping mechanism.

30 With these and other objects in view, the invention consists in certain constructions and in certain parts, improvements and combinations, as will be hereinafter fully described and then specifically pointed out in the claims hereunto appended.

40 In the accompanying drawings—Figure 1 is a plan view of so much of a wrapping mechanism as is necessary to an understanding of the invention, the wrapping mechanism proper being removed. Fig. 2 is a side 45 elevation, partly in section, of the construction shown in Fig. 1, the wrapping mechanism being shown in its proper position in said view. Fig. 3 is an end view of the construction shown in Fig. 1. Fig. 4 is a detail 50 view of the mechanism for transferring the wrapper to the wrapper presenting belt. Fig. 5 is a detail sectional view illustrating more particularly the blast mechanism for transferring the wrapper from the belt. 55 Fig. 6 is a detail view of one of the cams and

its connections. Fig. 7 is a detail sectional view of the mechanism for swinging the presenting belt, and Fig. 8 is a sectional detail view illustrating a modification.

Referring to the drawings which illustrate 60 a concrete embodiment of the invention, 1 indicates the frame which may be of any suitable configuration. In the construction shown, the wrapper, which is to be presented to the wrapping mechanism hereinafter de- 65 scribed, is cut in the machine by a die and a coöperating member, and in the preferred construction, the sheet or material from which the wrapper is cut will be retained in position with respect to the die by suc- 70 tion, though other suitable retaining devices might be employed. In general, the cutting mechanism, in the preferred form, will be substantially similar to that illustrated in the patent to R. L. Patterson and George 75 Arents, Jr., as the assignees of Oluf Tyberg, No. 654,203, dated July 24, 1900. Reference is made to this patent for a detailed description of the mechanism.

For the purposes of the present applica- 80 tion it is sufficient to say that a leaf of tobacco is placed on a perforated bed 2, said bed being provided with a knife 3 of suitable configuration. A suitable suction producing mechanism, such, for instance, as described 85 in the patent referred to, is caused to hold the leaf on the bed, after which the wrapper is cut by a roller 4 supported on an arm 5, this arm being mounted on a carriage 6. This carriage reciprocates in suitable ways 90 7 on the bed, this reciprocating movement being produced by a lever 9 which is connected to the carriage by a link 10. This lever is mounted on a shaft 11 suitably sup- 95 ported in the frame, said shaft having an arm 12 extending therefrom. This arm is connected by a link 13 to one of the arms 14 of a bell-crank lever 14—15, said lever being pivoted to a stud 16 mounted in the frame of the machine. The arm 15 of the bell- 100 crank lever is provided with the usual cam roller which engages a cam groove 17 in a suitably formed cam mounted on a cam shaft 18 suitably supported in the frame.

After the wrapper has been cut, it is, by 105 mechanism which will be hereinafter de- scribed, transferred to a wrapper presenting means. This means, in the preferred con- struction embodies a wrapper presenting 110 belt which may be mounted in various ways

and operated by widely varying constructions, and the wrapper may be held thereon in various ways. In the preferred form of the construction, and as shown, however, the belt, which is marked 19, will be provided with perforations 20 so that the wrapper may be held thereon by suction. While the suction mechanism may be, as has been suggested, of any suitable form, in the preferred construction and as shown, the belt will be mounted in a box 21 having a slotted top and bottom, the edges of the slots being shouldered, as indicated at 22, to form a guide for the belt. As illustrated, the belt is mounted on rollers 23 suitably supported in the box, and in the preferred construction, these rollers will be provided with grooves 24 which register with the rows of perforations in the belt.

20 The wrapper after being cut in the manner described hereinbefore, or by any other suitable mechanism, must be transferred to the belt. This may be accomplished in any suitable way and will preferably be accomplished by moving the bed on which the wrapper is cut. The mechanism by which the bed is moved to bring it into position to transfer the wrapper may be of any suitable description. As shown, the bed 2 and knife 3 are mounted on a plate 25 said plate being provided with a dove-tailed projection 25' which moves in a suitable groove 26' in a bed 26 mounted on the frame of the machine. The plate 25 has mounted on it a 25 stud 27', said stud being engaged by a forked lever 27 on a vertical shaft 28 suitably mounted in the frame of the machine. This vertical shaft has extending therefrom an arm 29 which is provided with a bowl 30 which engages with a suitable cam groove 31 in a cam mounted on the shaft 18 before referred to.

25 The suction is produced in the bed by means of a suitable suction mechanism, such, for instance, as a fan, not shown, the connections from the fan to the cutting bed including suitable pipes, such, for instance, as pipes 32. In order that the suction may not be cut off during the movement which 50 the bed is given to bring the wrapper into suitable position to be transferred to the belt, suitable telescopic connections are provided, these connections including short tubes 33 (see Fig. 4) which are connected to the bed, said tubes telescoping into the pipes 55 32 when the bed is given its movement.

50 The movement of the cutting bed hereinbefore referred to positions the wrapper in the particular construction shown, beneath the under run of the belt, so that it may be readily transferred to the belt. The construction by which the transfer of the wrapper from the cutting bed to the belt is effected may be of any desired character, but 65 it will preferably be effected by moving the

bed. In the construction shown, the bed is provided with a depending lug 34 (see Fig. 4 and dotted lines in Fig. 1) which moves in suitable guides 35 secured to the plate 25. When the cutting bed has been shifted in 70 the manner hereinbefore described so as to bring the cut wrapper into position beneath the under run of the belt, this depending lug 34 comes over and registers with a plunger 36 mounted on the bed 28 which bed is 75 suitably secured to the main frame. This plunger 36 has on its lower end a collar 37 which is engaged by a forked lever arm 39 extending from a hub 40, said hub being supported on a stud 41 carried on a bracket 80 attached to the main frame of the machine. This hub 40 has extending from it a second arm 42 which is provided with a suitable bowl engaging with a cam groove in a cam 43 mounted on the shaft 18 before referred to. The cam is so shaped that when the cutting bed carrying the cut wrapper comes into position beneath the under run of the belt, it will, through the mechanism described, 85 raise the bed, thus throwing the wrapper up against the suction belt which at this time will be stationary. While the suction might be cut off to permit the transfer of the wrapper, in the preferred form of the construction, the suction operating through the perforations 20 in the belt will be strong enough to take the wrapper from the suction bed.

90 After the wrapper has been transferred by the mechanism described, or by any other 100 suitable mechanism, to the belt, the belt will be caused to travel in order to bring the wrapper into proper position so that it may be presented to the wrapping mechanism. The movement of the belt may be effected 105 by agencies which differ widely in construction. In the construction shown, one of the 110 rollers 23 has its shaft 44 extended outward from the box and to this shaft is connected a flexible shaft 45, the connection being effected by means of a collar 46 or in any other desired manner. This flexible shaft 45 has its other end supported in a bearing 47 which is supported in a bracket 48 extending outwardly from the machine frame. 115 The end of the shaft 45 is provided with a spiral gear 49 which meshes with another spiral gear 50, this spiral gear being supported on a stud 51 mounted in the main frame of the machine. Mounted on this 120 stud 51 is a gear 52, the said gear being fast to the spiral gear 50. This small gear 52 is at proper times actuated by a segment rack 53 secured to a disk 54 mounted on the shaft 18 before referred to. It will be seen that 125 through the construction which has just been described, the belt will be given an intermittent traveling or rotating movement, the segment rack 53 being long enough to produce a sufficient movement of the belt to 130

cause the wrapper to be delivered to the wrapping mechanism.

The wrapping mechanism may be of any desired construction, and may be located in any desired position with respect to the belt. In the preferred construction, however, and as shown in Figs. 2 and 3, the wrapping mechanism will be located over the belt. The construction of wrapping mechanism illustrated in Figs. 2 and 3 is in its general features of the type disclosed in the patent to Reuse No. 552,447, granted December 31, 1895. The wrapping will be effected by means of pairs of intermeshing jaws operating through suitable gearing in the manner generally indicated in the said Reuse patent.

In the construction shown in Fig. 8, the wrapping mechanism indicated is of the ordinary roller form, the rolls being marked 56, and these rolls are located at one end of the belt instead of over it, as is the case in the other figures. It is obvious that the wrapping mechanism might be placed under the belt if desired, but this modification being obvious no illustration is deemed necessary.

The wrapping mechanism may take the wrapper from the presenting belt in various ways, but there will preferably be employed positive agencies for transferring one end of the wrapper to the bunch or other object in the wrapping mechanism. In the construction shown, this transferring mechanism consists of a blast mechanism. In the construction shown in Figs. 1, 2, 3 and 5, there is provided a blast pipe 57, said pipe communicating with a suitable blast mechanism, not shown, and this pipe communicates with a guide 58 which is formed in one of the walls of the box 21. Connecting with this guide is a short bent pipe 59, the opening in which registers with a line of the perforations 20 in the belt. This blast may act either constantly or intermittently, as desired. In the construction referred to, when the point of the wrapper reaches the proper position beneath the jaws it also overlies the opening in the blast pipe and is blown upward by the blast into the grasp of the jaws.

The construction shown is intended for wrapping tapering cigars. In order that the wrapper may be properly presented to the cigar, means are provided for effecting a relative angular movement between the presenting belt and the wrapping mechanism during the wrapping operation. While this might be accomplished in various ways, in the best constructions, it will be effected by swinging the presenting belt. The mechanism for thus swinging the presenting belt may be varied within wide limits. In the construction shown, see more particularly Figs. 3 and 7, the frame is provided with a

circular boss or collar 60 and the box 21 is provided with a downward projecting tubular extension 62 which projects through the boss, the box being provided with a shoulder so as to be seated on the boss. The lower end of this tubular extension 62 is provided with a segment gear 63 which is engaged by a segment 64 mounted on a lever 65, said lever being pivoted on a stud 66 depending from the under side of the frame. The lever 65 carries on its other end a bowl 67 which engages with a cam groove 68 in a cam mounted on the shaft 18 before referred to.

When the machine is to spirally wind a wrapper about an article to be wrapped, as is the case in wrapping cigars, for instance, a relative traversing movement will be effected between the wrapper presenting belt and the wrapping mechanism. While this may be effected in various ways, in the preferred construction, it will be effected by causing the wrapping mechanism to receive a bodily traversing movement. The traversing movement may be effected in any desired manner, as, for instance, in the manner illustrated in the patent granted to Patterson and Arents, as assignees of Oluf Tyberg, No. 654,195, dated July 24, 1900. In the construction illustrated, the wrapper carrying jaws and the gears and shaft which operate them are mounted in a frame 69 mounted on two rods 70 which are supported in arms 71 extending upward from the frame of the machine. The gears which drive the jaws receive their motion primarily from a long gear 72 mounted on a shaft 73 journaled in the arms 71, this shaft being driven in any suitable manner, as, for instance, by a belt pulley 74. One of the gears which forms a part of the train which drive the jaws, as, for instance, the gear marked 75, is constantly in mesh with the long gear 72. The traversing movement of the wrapping mechanism is effected by means of a lever 76 pivoted at 77 in a bracket on the side of the frame, this lever being connected to the frame 69 by means of a link 78. The other end of this lever 76 is provided with a bowl which engages a suitable groove in the side of a cam drum, this drum being the one in which the cam groove 68 before referred to is formed.

Changes and variations may be made in the mechanisms by which this invention is carried into effect. The invention is not, therefore, to be limited to the specific details of construction hereinbefore described and illustrated in the accompanying drawings.

What is claimed is:—

1. The combination with a wrapping mechanism, of a wrapper presenting means, a carrier in which said means is mounted to rotate, devices for rotating said wrapper

presenting means to deliver the wrapper, means for giving the carrier an angular movement, and means for giving the wrapping mechanism a traversing movement, substantially as described.

2. The combination with a wrapping mechanism, of a wrapper presenting belt, means whereby the wrapper is secured to the belt, a carrier in which said belt is rotatably mounted, means for rotating the belt, means for giving the carrier an angular movement, and means for giving the wrapping mechanism a traversing movement, substantially as described.

3. The combination with a wrapping mechanism, of a perforated wrapper presenting belt, a suction mechanism acting through the perforations to secure the wrapper to the belt, a carrier in which the belt is rotatably mounted means for rotating the belt, and means for producing during the wrapping operation a relative movement between the belt and the wrapping mechanism which is the resultant of an angular movement of one of these members and a traversing movement of the other, substantially as described.

4. The combination with a wrapping mechanism, of a perforated wrapper presenting belt, a suction mechanism acting through the perforations to secure the wrapper to the belt, a carrier in which the belt is rotatably mounted means for rotating the belt, means for giving the carrier an angular movement during the wrapping operation, and means for giving the wrapping mechanism a traversing movement during the wrapping operation, substantially as described.

5. The combination with a wrapping mechanism of a suction belt wrapper presenting mechanism located beneath the wrapping mechanism, and means for causing the belt to travel beneath the wrapping mechanism to present the wrapper to the wrapping mechanism, substantially as described.

6. The combination with a wrapping mechanism, of a suction belt wrapper presenting mechanism located beneath the wrapping mechanism, means for causing the belt to travel beneath the wrapping mechanism to present the wrapper to the wrapping mechanism, and means for producing a relative angular movement between the belt and the wrapping mechanism during the wrapping operation, substantially as described.

7. The combination with a wrapping mechanism, of a suction belt wrapper presenting mechanism located beneath the wrapping mechanism, means for causing the belt to travel beneath the wrapping mechanism to present the wrapper to the wrapping mechanism and means for producing during

the wrapping operation a movement between the belt and the wrapping mechanism which is the resultant of an angular movement of one of these parts and a traversing movement of the other part, substantially as described.

8. The combination with a wrapping mechanism, of a suction belt wrapper presenting mechanism located beneath the wrapping mechanism, means for causing the belt to travel beneath the wrapping mechanism to present the wrapper to the wrapping mechanism, and means for producing during the wrapping operation an angular movement of the belt and a traversing movement of the wrapping mechanism, substantially as described.

9. The combination with a wrapping mechanism, of a perforated presenting belt located beneath said mechanism, suction devices coöperating with the belt, the suction operating through the perforations in the belt, a suction cutting bed, means for cutting a wrapper on the bed, means for producing a relative movement between the bed and the belt, whereby the bed is caused to deliver the wrapper to the under run of the belt, and means for rotating the belt to cause it to present the wrapper to the wrapping mechanism, substantially as described.

10. The combination with a wrapping mechanism, of a perforated presenting belt located beneath said mechanism, suction devices coöperating with the belt, the suction operating through the perforations in the belt, a suction cutting bed, means for cutting a wrapper on the bed, means for producing a relative movement between the bed and the belt, whereby the bed is caused to deliver the wrapper to the under run of the belt, means for rotating the belt to cause it to present the wrapper to the wrapping mechanism, and means for giving the belt an angular movement during the wrapping operation, substantially as described.

11. The combination with a wrapping mechanism, of a perforated presenting belt located beneath said mechanism, suction devices coöperating with the belt, the suction operating through the perforations in the belt, a suction cutting bed, means for cutting a wrapper on the bed, means for producing a relative movement between the bed and the belt, whereby the bed is caused to deliver the wrapper to the under run of the belt, means for rotating the belt to cause it to present the wrapper to the wrapping mechanism, means for giving the belt an angular movement, and means for giving the wrapping mechanism a traversing movement, said movements occurring during the wrapping operation, substantially as described.

12. The combination with a wrapping mechanism, of a perforated belt, suction de-

- vices coöperating with the belt, whereby the wrapper is held to the belt, means including a flexible driving connection for rotating the belt to cause it to deliver the 5 wrapper to the wrapping mechanism, means for swinging the belt with respect to the wrapping mechanism during the wrapping operation, and means for giving the wrapping mechanism a traversing movement during the wrapping operation, substantially as described.
13. The combination with a wrapping mechanism, of a suction box, a perforated belt mounted therein, means for rotating the belt to deliver a wrapper to the wrapping mechanism, and a blast mechanism for transferring the end of the wrapper from the belt to the wrapping mechanism, substantially as described.
14. The combination with a wrapping mechanism, of a suction box, a perforated belt mounted therein, means for rotating the belt to deliver a wrapper to the wrapping mechanism, a blast mechanism for 10 transferring the end of the wrapper from 15 20 25

the belt to the wrapping mechanism, and means for swinging the box with respect to the wrapping mechanism during the wrapping operation, substantially as described.

15. The combination with a wrapping mechanism, of a suction box, a perforated belt mounted therein, means for rotating the belt to deliver a wrapper to the wrapping mechanism, a blast mechanism for transferring the end of the wrapper from the belt to 30 the wrapping mechanism means for swinging the box with respect to the wrapping mechanism during the wrapping operation, and means for giving the wrapping mechanism a traversing movement during the 35 40 wrapping operation, substantially as described.

In testimony whereof, I have hereunto set my hand, in the presence of two subscribing witnesses.

SYDNEY I. PRESCOTT.
